UNITED STATES PATENT OFFICE.

JOSEPH D. DUSENBURY, OF NEWTON, MASSACHUSETTS.

DOUBLE CUTTING TOOL FOR PLANERS.

Application filed July 31, 1920. Serial No. 400,365.

To all whom it may concern:

Be it known that I, JOSEPH D. DUSENBURY, a citizen of the United States, residing at Newton, in the county of Middlesex 5 and State of Massachusetts, have invented new and useful Improvements in Double Cutting Tools for Planers, of which the following is a specification.

My invention relates to planing tools for metal and specifically to double acting cutters, known as duplex planing tools. In planing machines, the tool is mounted above the work table or platen, which has a reciprocatory movement back and forth under 10 the tool. The work is placed on this table and as it passes under the tool, a chip is cut therefrom extending the whole length of the work.

Either a single acting or double acting 20 cutter may be used. In the case of a single acting cutter, there is only one tool and this tool cuts on the forward movement of the table only; while in case of a double acting cutter, there 25 are two tools and a cut is made both on the forward movement of the table and on the reverse movement. At the end of a forward and reverse movement of the table, the cutter is shifted transversely of the line 30 of travel of the table, so that at the next movement of the table, a new cut will be made parallel to the preceding one. Each cut is made to overlap the preceding, a certain amount so that no portions will be left unplaned. It is desirable to vary the amount 35 of this overlap in certain cases and for certain kinds of work. This may be accomplished with single acting cutters by varying the distance the cutter is shifted transversely of the table, after the completion of 40 each cut. In the case of double acting cutters in use at present, the overlap for the return cut with respect to the forward cut is of a fixed width and it is the object of my 45 invention to produce means whereby the overlap of the return cut over the forward cut in the case of a double acting cutter may be varied.

Another object is to produce a device 50 whereby a tool holder may be readily attached to the clapper of a planing machine.

Referring now to the drawings,—

Figure 1 is an elevation of the tool holder partly in longitudinal section.

Figure 2 is a side elevation of the same.

Figure 3 is a plan view of the holder.

Figure 4 is a detail sectional view on line 4—4 of Figure 1 showing the means of holding the cutter adjustably in place.

Figure 5 is a section on line 5—5 of Figure 1, showing the relative position of the cutters in one position of adjustment.

Figure 6 is a diagrammatic view of the cutting action of the cutters when adjusted, as in Figure 5.

Figure 7 shows my device adjusted for cutting rising surfaces.

Figure 8 is a form of clapper showing angularly placed grooves therein in which the tool may be mounted at an angle to the work in cutting raised surfaces.

Figure 9 shows in front elevation my duplex tool holder secured to the clapper of a planing machine and a form of brace for steadyng the clapper.

Figure 10 is a side elevation thereof.

Figure 11 shows in detail a form of brace.

Figure 12 is a detail of a slightly different form of brace member.

Figures 13 and 14 show details of the device shown in Figure 12.

Figure 15 shows still another form of the brace.

I will now describe my device in detail, referring to the various parts thereof, by reference numerals. 10 designates a head or clapper box, in which are pivotally mounted clappers 12 and 12^a, in which suitable cutting tools 11 and 11^a may be adjustably secured.

Extending from the upper side of the clapper box is a shank or stem 13, preferably cylindrical, and provided with a reduced screw threaded portion at its upper end. This stem is mounted for angular adjustment in a supporting sleeve 14, which is supported on the planing machine in any manner usual or suitable in or for such a machine with the necessary provision for relative cutting and feeding movement between the work carrying table or platen and the cutter. The feature of angular adjustment of a double acting cutter, I believe to be new.

It will be noted also that with this construction the tools are mounted closely adjacent the axis of their support and on opposite sides thereof, equally spaced therefrom, their cutting edges facing this axis so that during the operative stroke of each tool it is pulled against the work and the spring of each tool, due to its distance from

the axis of the support, is small and the same for both tools.

Threaded on to the reduced end of the stem 13 is a nut 23, which is provided with a flange adapted to bear on the upper end of the sleeve 14. By means of the nut 23, the head may be drawn up tightly against the lower end of the sleeve 14 and on the lower end of this sleeve may be formed a flange 24, extending outwardly therefrom and affording an extended surface, as an abutment for the clapper box. This flange 24 and the top of the clapper box may be roughened or provided with teeth in order to more effectively hold the head in adjusted position relative to the sleeve.

In effecting the angular adjustment of the cutting tools, the nut 23 is loosened and the head 10 turned to any position desired in which the respective cuts of the forward cutting tool and the return cutting tool will overlap. Such a position, is illustrated in Figure 5 of the drawings, in which A—A represents the direction of travel of the platen or work table, and B—B is the line through the center of the cutters lying at an angle to the line A—A. It will be noted that each of the cutters extends slightly across the line A—A and the sum of these extensions represents the distance that the return cut will overlap the forward cut.

The cuts, which the tools will make when in this position is diagrammatically represented in Figure 6, in which the line Y indicates the direction in which the tool is fed across the work table or platen, and the arrows α , α' , respectively indicate the directions the work table is traveling in making the forward and return cuts. It will be noted that the positions of the forward cut and the succeeding return cuts are such that they slightly overlap. It will be noted also that the next forward cut in a similar manner, overlaps the preceding return cut and so on. After each return cut, the tool is moved along the line Y in the direction of the arrow, transversely of the travel of the work, a distance equal to the sum of a forward and return cut minus the space of two overlaps; this distance is indicated at y' of Figure 6. The clappers 12 and 12^a are provided with grooves 20 in which the tools are held for longitudinal and angular adjustment by means of bolts 16 passing through apertures in the clappers. These bolts are provided at their head ends 17 with slots 19, adapted to receive the tools slidably therein and the opposite ends of the bolts are provided with a reduced screw-threaded portion 18 in cooperation with which the tools may be held in adjusted position by means of nuts 21 threaded thereto.

The clappers are limited in their pivotal movement by abutments 22 attached to the clapper box so that the tools 11, as shown in

Figure 1, will be in cutting position as the work table moves forward i. e. to the right, and the tool 11^a will be free to drag on the surface of the work in an operative position. When the work table moves in the opposite direction the reverse action will take place.

In Figure 7, I show the adjustment of the tool for cutting rising surfaces. It will be noted that the tool in this case is adjusted to an angle of inclination to the surface being cut. This is necessary to enable the cutter which is inoperative on either the forward or return stroke, as set forth above, to swing free from the work thereby avoiding scarring or otherwise damaging the work. The angular adjustment of the tool to the rising surface may be accomplished through the overhead adjustment device of the planer. In the operation of cutting a rising surface, the feed is downwardly, and the tool which cuts on the forward stroke is adjusted to extend below the tool which cuts on the return stroke, a distance equal to the width of a cut minus the width of an overlap. In other respects than those set forth above, the cutting on a rising surface is the same as that on a horizontal surface.

In Figure 8 is illustrated a form of clapper designed to permit approximate adjustment of the cutters to a rising surface, independently of the tool holder in which they are mounted. The clapper designated 12^a is provided with a groove 20^a extending longitudinally of the clapper. Diagonally crossing the groove 20^a and at angles of less than 90° thereto, are grooves 20^a and 20^b designed to receive a cutter for cutting rising surfaces. The cutter is placed in one of these grooves 20^a and 20^b according as the rising surface is a left hand or right hand surface, roughly adjusted to the rising surface, the fine adjustment of the cutter to the surface being effected by adjusting the tool in which the cutters are mounted through the overhead adjustment.

In the cutting of rising surfaces, it will be obvious from the above construction that the tools may be angularly adjusted in the sleeve 14 to compensate for any unevenness or irregularity of the cuts of the two tools as primarily adjusted.

The usual planing machine is provided with a cross feed for moving the tool secured thereon transversely of the work table (not shown). The cross feed comprises a carriage or saddle 30 (see Figs. 9 and 10) mounted for slidable adjustment on guideways 30^a and is provided with an adjusting screw 30^b. The vertical adjustment of the tool to and from the work is provided for by means of a slide 31 vertically adjustable on a guideway 32 by means of an adjusting screw 31^a. The guideway 32 is swiveled to the saddle 30 at 32^a affording angular adjustment for the tool,

which may be known as the primary angular adjustment.

A clapper box 33 is swiveled to the lower end of the slide 31 to provide an additional angular adjustment in the nature of a swivel and which may be known as the secondary angular adjustment. The clapper box is provided at its upper end with an arcuate member 35 having an arcuate slot 36 there-
10 in concentric with the swivel of the clapper box and bolts 37 secured in the slide 31 and projecting through the slot 36 and nuts 38 are provided to hold the clapper box in angular adjustment to the slide 31.
15 Within the clapper box, a clapper 34 is pivotally mounted by means of a bolt 34^a and extending transversely of the clapper are straps 39 and 40 adjustable on bolts 42 to hold a tool on the clapper. Nuts 41 are
20 threaded on the bolts to hold the straps in adjusted position.

It is desirable to attach the tool holder to the clapper of the machine in the same manner that an ordinary tool is attached thereto, but if the tool holder should be secured to the clapper 34 without means for holding the clapper against pivotal movement, a double clapper action would result on the forward cut which would be objectionable. In order to eliminate this objection I have devised a means for clamping the clapper 34 of the machine against pivotal movement in its clapper box which may be readily attached or detached to any planing machine now in use without alteration of the machine.
30
35

One form of this device is shown in Figs. 9, 10 and 11 and comprises a bracket 43 and a brace 44. The bracket is provided with a triangular flange 45 having formed there-
40 in notches 46 adapted to receive the bolts 37 for removably securing the bracket to slide 31. A set screw 45^a is adjustably fitted in an aperture in the apex of the flange 45, the end of which is adapted to rest against the slide to steady the bracket and the outer end of the bracket is provided with a recess 43^a on its under side. The brace 44 comprises a tubular member 47 in the upper end of which is inserted a plug 48 provided intermediate of its ends with an outstanding flange 49 which is adapted to rest on one end of the tubular member. On the upper end of the plug is a spherical head 50 adapted to fit in the recess 43^a providing universal movement of the brace.
50
55

In the opposite end of the bore of the tube 47 may be inserted the screw threaded end of a bolt 51, the opposite end of which is provided with a head 52 having a notch 52^a therein. The head 52 is adapted to abut against suitable means on the clapper, as the strap 40, with said means preferably resting within the notch 52^a thereof. In this manner the clapper will be held positively

braced against movement about its pivot. Threaded on to the bolt 51 is an adjusting nut 53 by which the length of the brace may be adjusted to suit variations of the dimensions of a machine on which the device may be used. The nut also serves as an abutment adapted to rest against the lower end of the tube to hold the parts in adjusted position.
70

A device of the nature described above 75 may be readily attached to a planer and by means thereof, my duplex tool holder may be attached to the clapper of a planing machine in the same manner as any ordinary tool. By means of the adjustment of the brace 80 member the bracing device may be adapted to variations in length of clapper boxes of various planing machines, and by means of the ball and socket connection with the bracket arm remains effective when the clapper box is adjusted at an angle to the slide.
85

The bracket may be allowed to remain permanently attached to the bolts 37 when my tool holder is removed without interference with the operation of any other tool secured to the clapper 34. A further advantage of securing the clapper 34 by the above means is that there is provided thereby a slight give or elasticity to the bracing of the clapper which has a tendency to relieve the shock against the return tool in coming in contact with the work. The importance of this will be appreciated when it is understood that the return stroke of the work table is ordinarily more rapid than the forward stroke and therefore the shock on the return tool is greater.
90
95
100

The specific form of my bracing device may vary from that illustrated in Figs. 9 to 11 inclusive without departing from the spirit of the invention, as for instance the stem of the plug 48 may be swiveled to the bracket 43 by means of a pin 55 (see Figs. 12, 13, and 14). The notch 56 in the head 52 of bolt 51 in this case is preferably curved so as to positively grip the strap 48 in any angle of adjustment of the clapper box 33. Or a brace 44^b of the form shown in Fig. 15 may be provided in which the bolt at the lower end is dispensed with and a tubular member 47^b is provided having a notch 52^b formed in its lower end adapted to fit the strap 40. In this form of the device the adjustment in length may be accomplished by means of a screw threaded bolt 48^b having 110

a nut 53^b, adjustably mounted thereon, said nut being adapted to rest on the upper end of the tubular member. The upper end of the nut is preferably provided with a head 50^b having a rounded upper surface adapted for universal movement in a socket 43^b in the bracket 43.
115
120
125

While this invention has been described as applied to a planer it will be quite evident to those skilled in the art that a similar con- 130

struction might be applied to shapers, if desired, or to any machine having planular traverse between the work and tool.

Having thus explained the nature of my 5 said invention and described a way of making and using the same, altho without attempting to set forth all of the forms in which it may be made or all of the modes of its use, what I claim is:—

10 1. In a planing machine having a pair of cutting tools, means for carrying said tools in a common plane, said means being rotatively adjustable to cause this plane to assume an angle to the direction of cutting 15 stroke of said tools.

2. In a duplex planing mechanism, a clapper box, a stem extending therefrom, two cutting tools mounted in said clapper box, a sleeve in which said stem is swivelled 20 for adjustment therein, and means to hold the parts in adjusted position.

25 3. In a duplex planing mechanism, a clapper box, a stem extending therefrom, two cutting tools acting oppositely to one another mounted in said clapper box, a sleeve in which said stem is mounted so as to be free to turn about its axis to adjust the position of the cutting tools relative to each other and to the line of travel of the work 30 table, and means for holding the parts in adjusted position.

35 4. In a duplex planing mechanism, a head, a relatively movable work table, a clapper box carried by said head, and cutting tools carried by said box and adapted to cut, one on the forward movement of the work table and the other on the return movement thereof, said clapper box being adjustable about an axis angularly disposed relative to said 40 table so that the overlap of the forward and reverse cuts may be varied.

45 5. In a duplex planing mechanism, a pair of cutting tools acting to cut on reverse directions of relative movement between them and the work, and means whereby the tools may be adjusted as a unit to vary the overlap of the cutting paths of the tools.

50 6. A device for holding a clapper against pivoted movement comprising a relatively fixed bracket, a member having one end pivoted to said bracket, a sleeve mounted thereon, a bolt having a head at one end and screw threads at the opposite end extending into the sleeve, a notch in the head for engaging over a strap or the like on said clapper, and a nut on the screw threaded end of the bolt for adjusting the length of the device.

60 7. In combination with the tool carriage of a planing machine having a clapper box thereon, and a clapper pivotally mounted in said clapper box, of means for holding said clapper against pivotal movement comprising a bracket arm secured to the carriage, a member comprising a sleeve having an ex-

65 tension thereon pivoted to said bracket, a bolt having one end screw threaded to said sleeve, and a head at the other end of said bolt having a notch therein adapted to fit over a member on said clapper, said screw threaded end carrying a nut, whereby the 70 length of said means may be adjusted.

8. In combination with the tool carriage of a planing machine having a clapper box thereon and a clapper mounted in said clapper box, of means for clamping said clapper against 75 pivotal movement comprising a bracket and a brace, said bracket being provided with a semi-spherical socket, and said brace comprising a tubular member having a spherical head at one end thereof adapted to fit said socket, a bolt having a notched head at one end, and a screw threaded end adapted to be inserted into the lower end of said tubular member, and a nut on said threaded portion whereby the brace member may be adjusted 80 to bring the notched head against said clapper.

9. A device for holding a clapper stationary, comprising a bracket adapted to be carried in fixed relation to said clapper, said bracket having a socket formed therein, a brace adjustable as to length and having one end adapted to fit in said socket for universal movement therein and the opposite end adapted to bear against said clapper. 95

10. A device for holding a planer clapper stationary comprising a brace adjustable as to length, a bracket adapted to be secured to the planer against which one end of the brace is adapted to rest, the opposite end of the brace being provided with a notch to receive a projecting portion on the clapper. 100

11. In a planing machine having a pair of cutting tools, means for carrying said tools in a common plane, said means being adjustable to move the tools in opposite directions to cause this plane to assume an angle to the direction of cutting stroke of said tools. 105

12. In a planing machine, a support traversable in opposite directions and turnable about an axis, and a pair of tools carried by said support and yieldable toward said axis, their active portions facing toward said axis whereby each tool is active only when pulled against the work. 110

13. In a planing machine, a support turnable about its axis, and a pair of oppositely facing tools carried by said support to turn therewith closely adjacent said axis. 115

14. In a planing machine, a support turnable about its axis, and a pair of oppositely facing tools carried by said support to turn therewith closely adjacent said axis and equally spaced on opposite sides thereof. 120

15. In testimony whereof I have affixed my 125 signature.

JOSEPH D. DUSENBURY.
